UNITED STATES PATENT OFFICE.

ALBERT MOORE, OF SAN FRANCISCO, CALIFORNIA.

IMPROVEMENT IN PICKS OR AXES.

Specification forming part of Letters Patent No. 37,970, dated March 24, 1863.

To all whom it may concern:

Be it known that I, ALBERT MOORE, of the city of San Francisco, in the State of California, have invented a certain new and useful Improvement on Picks or Pick-Axes; and I do hereby declare the following to be a full, clear, and exact description thereof, reference being had to the accompanying drawings, and to the letters and marks thereon.

The drawings forming part of this specification show what is ordinarily called the "miner's" or "mining" pick constructed under my improvement, Figure 1 of these drawings representing, by an elevation, a pick attached to the handle as ready for use; Fig. 2 showing the pick and handle separate and apart; Fig. 3 showing the attaching portions of the pick and handle in place, the view being by longitudinal section; Fig. 4 being a view, by transverse section, of the socket at the lower end of the handle; and Fig. 5 being a view of the pick separated from the handle, the inner or attaching surface of the pick being shown.

In each of these figures, where like parts appear, like letters are used to designate the parts.

My improvement relates to means for connecting the pick to its handle, these means allowing of the ready detaching or attaching of the one to the other, and of the two being held firmly and close to each other when intended for use.

It is very important to the miner that he should have a pick which can be conveniently packed, readily attached to or detached from its handle, and that the means for attaching and detaching should be few, not liable to be lost, and strong and durable. It is also important that such means should not lessen the strength of the pick or the handle.

As originally constructed, and as used for many years, the miner's pick had an eye or socket at about its center, into which the handle was inserted and its end wedged. If the handle was left in while the miner was prospecting, the pick was carried with great inconvenience; if the handle was taken out and again fitted in when the use of the pick was required, trouble and delay necessarily resulted. The eye at about the center of the pick added to the expense of its manufacture, while it rendered the pick of less strength than it would be if solid or without the eye. Hence efforts

were directed toward making the miner's pick detachable. In one of the improvements of these efforts the handle is attached to the pick by a bolt which is passed through the eye and secured to the end of the handle by a key and straps; in another of these improvements straps, or a continuous band passed around the pick, are secured to the end of the handle. As will readily be perceived, material objections exist against both of these plans; the one has the objections of the weakness, from the eye, the number of pieces, and the expense; the other to the objections of not being means for securing firmly the pick to the handle, and of the interference of the band or straps in the use of the pick; while both are open to the objections of being expensive and the liability of the parts to work loose when in use.

My improvement is intended to remedy the evils of and remove the objections believed to exist against the miner's pick when detached from its handle.

As is shown by the drawings, the pick *a* has at or near its center a stout inward projecting piece, *b*, and the handle *c*, at its lower end a socket, *d*, firmly secured to it by the extension-pieces *e*, which embrace its edges. When the piece *b* is within the socket, a key, *f*, passed through the square hole *g* of the socket and a like hole, *h*, of the piece *b*, will firmly hold the pick to its handle. The end of the socket will be held closely to the pick, and in using the pick there will not be any working loose.

The key *f* may be solid and by a chain be hung to the handle, or it may be so split or divided up toward its base or broadest end as to be somewhat of a spring-key, and thus be, perhaps, less likely to work out.

The pick and the handle and the means of attachment, can be made of any of the materials usually employed. As will readily be seen, any individual can easily replace the handle if broken and repair the parts, or substitute others for them if needed.

In the place of the wooden handle and the socket, a cast handle with a recess and a square hole may be used.

When separated, the pick, handle, and key can very conveniently be carried or packed away, and in a moment be connected and put ready for use. The socket in the end of the

handle for the reception of the projecting piece of the pick and the hole for the reception of the key, being in and through metal only, makes all the surfaces of contact between the pick and the socket, and all the surfaces of strain of them, metal surfaces, thus rendering the connection of the pick and socket more durable and stronger than such connection would be if part of these surfaces named were of wood.

What I claim as my invention, and desire to secure by Letters Patent, is—

The pick *a*, with the projecting piece *b*, the socket *d*, and key *f*, constructed, combined, and arranged as herein set forth.

This specification signed this 2d day of September, 1862.
